UNITED STATES PATENT OFFICE.

EDWARD J. MOELLER, OF ST. LOUIS, MISSOURI.

NUT-CASTELLATING MECHANISM.

Application filed March 1, 1920, Serial No. 362,337. Renewed December 14, 1923.

To all whom it may concern:

Be it known that I, EDWARD J. MOELLER, a citizen of the United States, and residing at St. Louis, Missouri, have invented the 5 new and useful Improvement in Nut-Castellating Mechanism, of which the following is a specification:

This invention relates to mechanism adapted more particularly for castellating nut blanks.

One of the objects of this invention is to develop a mechanism adapted to castellate a nut blank by punching operation.

Another object is to develop mechanism 15 for castellating nut blanks which has a wide range of adjustment so as to adapt it for nuts of different sizes.

Another object is to develop mechanism 20 for castellating nut blanks by punching operations, whereby the punch and die mechanism is so constructed and arranged that it can readily be sharpened, repaired and replaced.

Further objects will appear from the detail description taken in connection with the accompanying drawings, in which:

Figure 1 is a plan of nut castellating mechanism embodying this invention;

Figure 2 is a front elevation;

Figure 3 is an enlarged section on the line 30 3—3, Figure 2;

Figure 4 is a section on the line 4—4, Figure 1;

Figure 5 is an enlarged section on the line 35 5—5, Figure 1;

Figure 6 is a detail showing a stem for mounting a nut blank; and

Figure 7 is a perspective view of a castellated nut blank.

Referring to the accompanying drawings, 40 1 designates a base which is arranged to be supported on the table 2 of any suitable punch press, the ram of this punch press being shown at 3. The base 1 may, however, 45 be mounted on a sub-frame or sub-base on the punch press as illustrated in application Serial Number 362,340, filed March 1, 1920.

The base is provided with recesses 4 arranged to receive die elements 5 which are 50 retained in position by clamps 6 secured by screws 7. The bottoms of these recesses are inclined as shown in Figure 5, while the bottoms of the die elements are correspondingly inclined so that the clamps serve to hold these die elements against the left

faces (Figure 5) of the recesses. The end face of the die elements 5 are beveled as shown in Fig. 4 so as to provide sharp cutting edges and the base is slotted as shown at 8 to provide for discarding of the punchings.

Guided in the base is a punch carrier 9 which is slotted to receive a punch 10 of T form arranged to cooperate with the die elements, and this punch is retained by a hardened gib 11 projecting slightly beyond the upper face of the punch carrier as shown in Figure 2 and which may be retained in position by a stirrup 12 and a set screw 13. The ram 3 of the punch is thus arranged to strike 70 the gib and transmit the blow to the punch through the gib. The punch carrier rests upon a head 14 at the upper end of a strong spring 15 carried by a stirrup 16 suspended from the table 2 and providing an abutment 75 connected to the spring. This spring is under tension and normally tends to hold the head 14 firmly against the bottom of the base. When, however, the ram 3 of the punch moves down, the spring will be compressed while the spring will return the carrier when the ram again rises.

Each die element has bearing thereon a set screw 17 threaded through a lug 18 on the base and provided with a lock nut 19. 85 Accordingly, the inner or cutting edges of these die elements may be accurately adjusted. Moreover, these die elements as well as the punch may be bodily removed to permit repair, replacement and adjustment of 90 the punch and die mechanism so as to cut slots of different sizes. It is to be understood, of course, that the punch carrier 9 may be readily removed, and that although the base of the punch itself is uniform the 95 tip, that is, that part cooperating with the die elements, is ground to various thicknesses corresponding to the width of the slot to be cut in the nut blank.

The base is arranged to receive a cap 20, 100 and this cap and base are machined to form a bearing for a carrier 21, which is flanged at 22 and is provided with a reduced portion 23 having a key way arranged to receive a key 24, this reduced portion being arranged to receive a ratchet 25 secured thereto by the key 24, and the extreme end of the reduced portion of the carrier being threaded to receive a collar 26 which secures the ratchet in position on the carrier and se- 110

cures the carrier in position in its bearings. Mounted on the reduced portion of the ratchet is a pawl carrier 27, which has a slotted arm 28 connected to an oscillating arm 29 which is oscillated by a cam on the ram 3, as shown in the application referred to, or in any other suitable manner. The pawl carrier further has a lug 30 on which is pivoted a pawl 31 which engages teeth 32 on the ratchet, there being in this case six teeth on the ratchet corresponding to the six faces of a hexagon nut.

Upon oscillation of the arm 29, the pawl carrier is oscillated, thereby causing the pawl 15 to successively move over the ratchet and move the carrier 21 step by step. In order to latch and retain the carrier in proper position during each movement, the ratchet 25, which is fixed to the carrier, is provided with a series of recesses 33 corresponding in number to the teeth 32, and these recesses are arranged to be engaged by a cone head plunger 34 mounted in a bore in the base and engaged by a spring 35. Accordingly, 20 upon each oscillation of the pawl, the carrier 21 is moved and the plunger will move out of one recess and into the next recess 33, the recesses being V shaped as shown in Figure 5.

Mounted in the carrier 21 is a holder 36, having a circular portion 37 and an angular portion 38 corresponding respectively to the outside diameter and the faces of the nut blank to be castellated. The faces of the 30 angular portion are slotted as shown at 39 to take over any burs which may be formed during the castellating operation. The holder has at its end a shoulder bearing against a frame 40 on its carrier, while both the carrier and holder are provided with key ways arranged to receive a key 41 to secure them together. The holder is retained in position by a clamping nut 42 and a lock nut 43, this lock nut being beveled 45 at 44 to permit ready entrance of a blank, and the nuts being recessed as shown at 45 to permit manipulation by a suitable tool.

Assuming the mechanism to be placed on the table of the punch press with proper 50 punch and die elements in position, and with the proper nut blank holder corresponding to the nut to be castellated clamped in the carrier; the operator will now place a nut blank 46, Figure 6, to be castellated on the reduced split tip 47 of a bar 48 and will insert the same through the holder, so that the crown of the nut will rest upon the die elements and with the punch interiorly of the blank. This will properly position 55 the blank with a crown between the punch and die and with the die externally of the projecting crown of the blank, and this blank will be interlocked with the holder. The operator will now depress the pedal of 60 the punch press causing a number of opera-

tions. At each operation the punch will move outwardly and will cooperate with the die so as to punch castellate the crown of the blank from the center thereof outwardly. Between the successive operations and 79 as the punch is again in the center of the blank, the ram, in rising, will move the pawl 31 to the left, Figure 2, so as to cause the holder to be moved through a predetermined angle corresponding to the angle 75 of the nut to be castellated. After the operations have been completed, the nut is withdrawn.

It will, therefore, be seen that this invention 80 accomplishes its objects. The crown of the nut blank is supported exteriorly by a stationary die with which cooperates an outwardly moving punch, and in view of the fact that the die as well as the punch is external to the holder, not only is a firm support provided for accurate work, but the die and punch elements can be accurately aligned. Moreover, this permits ready repair and replacement, for the punch, as well as the die, and the provision of the removable and replaceable holder, together with the adjustment and interchangeability of the punch and die, permits a wide range of adjustment to be attained, so as to provide for the castellation of nuts of different sizes. 85

It is obvious that various changes may be made in the details of construction without departing from the spirit of this invention; it is to be understood, therefore, that this invention is not to be limited to the specific 90 construction shown and described.

Having thus described this invention, what is claimed is:

1. In a machine of the character described, a die adapted to externally engage 105 a nut blank, a holder adapted to position the nut with respect to said die, a punch adapted to cooperate with said die to castellate the blank, and means for moving said holder rotatively in timed relation to said punch.

2. In a machine of the character described, a die adapted to externally engage the nut blank, a rotatable holder adapted to 115 detachably receive the nut blank therein and position the same with respect to said die, and a punch adapted to cooperate with said die to castellate the blank.

3. In a machine of the character described, a die, a punch carrier having a punch cooperating with said die, a holder adapted to position a nut blank to a series of oriented positions between said punch and said die and against said carrier, and means for operating said punch. 120

4. In a machine of the character described, a die, a punch carrier having a punch cooperating with said die, a holder adapted to position a nut blank on said die and against said carrier to a series of 125

oriented positions with said punch inside of the blank, and means for operating said punch.

5. In a machine of the character described, a die adapted to externally engage a nut blank, a punch cooperating therewith, a holder adapted to position a nut blank to a series of oriented positions between said punch and said die, and a rotatable carrier for said holder.

6. In a machine of the character described, a die adapted to externally engage a nut blank, a punch cooperating therewith, a holder adapted to position a nut blank to a series of oriented positions between said punch and said die, and a rotatable carrier detachably supporting said holder.

7. In a machine of the character described, a die adapted to externally engage a nut blank, a punch cooperating therewith, a rotatable holder adapted to position a nut blank to a series of oriented positions on said die, and means for rotating said holder.

8. In a machine of the character described, a die adapted to externally engage a nut blank, a punch cooperating therewith, a rotatable holder adapted to position a nut blank to a series of oriented positions on said die, and means for rotating said holder while retaining the blank on said die.

9. In a machine of the character described, a die adapted to externally engage a nut blank, a punch cooperating therewith, and a rotatable holder adapted to position a nut blank to a series of oriented positions with its circular crown between said punch and said die.

10. In a machine of the class described, a vertically reciprocating punch, and means for holding a nut blank to permit punch-

ing of the blank from the center opening outwardly to form slots while the longitudinal axis of the blank is in horizontal position.

11. In a machine of the class described, a vertically reciprocating punch, and means for holding a nut blank to permit entry of said punch in the center opening of the blank and to produce slots while the longitudinal axis of the blank is in horizontal position.

12. In a machine of the class described, a vertically reciprocating punch, and movable means for holding a nut blank to permit entry of said punch into the center opening of the blank and to produce slots while the longitudinal axis of the nut blanks is in horizontal position.

13. In a machine of the class described, a vertically reciprocating punch, and a nut blank holder, said punch and holder cooperating to permit entry of said punch into the center opening of said nut blank and to produce slots while the longitudinal axis of the blank is horizontal.

14. In a machine of the class described, a vertically reciprocating punch, and a carrier supporting the nut blank in position to permit said punch to enter the center opening of said blank and to produce slots while the longitudinal axis of the blanks is in horizontal position.

15. In a machine of the class described, a carrier for nut blanks to be castellated, a vertically reciprocating punch, means for introducing said punch into the bore of the nut, and means for passing the punch through the wall of the nut when the latter has its longitudinal axis in horizontal position.

In testimony whereof I affix my signature this 5th day of January, 1920.

E. J. MOELLER.
